CLAIM

The ornamental design for a telescopic sight, as shown and described.

DESCRIPTION

FIG. 1 is a front perspective view of a telescopic sight showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top pan view thereof; and,

FIG. 7 is a bottom pan view thereof.

The broken line in the drawings depicts unclaimed portion of the telescopic sight only and forms no part of the claimed design.
